UNITED STATES PATENT OFFICE

2,228,428

SPRINKLER

John H. Wilson, North Platte, Nebr.

Application January 4, 1940, Serial No. 312,431

3 Claims. (Cl. 299—50)

This invention relates to an automotive sprinkler.

An object of the invention is the provision of a sprinkler which is driven along a definite path on a lawn by means of power developed from the pressure of water which is sprayed over the lawn through revolving arms, the body of the sprinkler being cast with a central passage to conduct water from a hose to a motor including the revolving arms, the sprinkler being guided along the definite path by a grooved wheel supported at the forward end of the body which moves over the hose that supplies the water.

A further object of the invention is the provision of an automotive sprinkler which is moved along a definite path on a lawn by a toothed wheel operated by a water motor supported by a body which has a guiding wheel at the forward end, spaced arms being provided for maintaining the body in an upright position when the body is guided around a curved path with flanges projecting from the body for maintaining the hose in line with the propelling wheel at the rear end of the sprinkler when the sprinkler is moved around a curve.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

35 In the drawings:

Figure 1 is a view in side elevation of a sprinkler constructed in accordance with the principles of my invention.

Figure 2 is a plan view of the same.

40 Figure 3 is a vertical section taken along the line 3—3 of Figure 2.

Figure 4 is an enlarged fragmentary vertical section taken along the line 4—4 of Figure 2.

45 Figure 5 is a fragmentary view in elevation of the modified form of the power wheel.

Referring more particularly to the drawings 10 which designates a body which is cast in one piece as shown more particularly in Figure 3 and this body is provided with a horizontal conduit 11 which extends from the rear end to approximately the center thereof. The rear end of the body is provided with a nipple 12 in line with the conduit 11 and to this nipple is connected a flexible hose 13 of the usual construction.

50 The inner end of the conduit opens into a down

turned passage 14 which is ordinarily closed by a plug 15 so that when the plug is removed the conduit 11 may be cleaned as desired. The interior of a hollow post 16 may be reached through the opening 14.

The forward part of the body 10 is reduced in size and is provided with a horizontally disposed flat portion 17 and an upwardly curved portion 18. A depending flange 19 is formed between the intersection of the flat portion 17 and the curved member 18.

5 The forward part of the body 10 is reduced in size and is provided with a horizontally disposed flat portion 17 and an upwardly curved portion 18. A depending flange 19 is formed between the intersection of the flat portion 17 and the curved member 18.

A handle 20 is secured in an approved manner as shown at 21 to the curved portion 18 while the opposite end of the handle as shown at 22 is secured to the top of the flat portion 17.

15 The forward end of the curved member 18 is provided with a vertical passage 23 which receives a pintle 24 formed at the upper end of a fork 25. A pin 26 maintains the pintle in position on the end of the member 18. However, a nut and washer may be employed for the purpose.

A grooved wheel 30 is mounted upon an axle 31 which is supported by the lower ends of the arms of the yoke 25. This grooved wheel is adapted to ride over a length of the hose 13 for 25 guiding the sprinkler along a definite path on the lawn.

20 A transverse bar 32 is secured in any approved manner as by screws or bolts 33 to the top of the flat portion 17. Rearwardly inclined arms 34 depend from the ends of the bar 32 upon opposite sides of the flat portion 17 and the lower ends of these arms are curved rearwardly as shown at 35. The curved portions 35 act as runners to engage the ground when the sprinkler is being 35 carried around a curved path to prevent the sprinkler from falling to one side.

25 A pair of plates 36 located at each side of the body member and secured in any approved manner as by bolts 37 to the side flanges 38 depending 40 from the opposite side edges of the flat portion 17 are adapted to engage the hose 13 when the sprinkler is being moved through a curved path for aiding in maintaining the body member and likewise the spaced power wheels 40 and 41 in 45 alignment with the hose. The plates 36 depend sufficiently below the lower edge of the body member in order to engage the hose during the turning movement of the sprinkler.

30 A pair of brackets 42 may be cast integrally 50 with the body 10, are located in spaced relation and extend forwardly of the hollow post 16. These brackets are provided with bearings for supporting a shaft 43 to which is secured in any approved manner a gear 44. This gear meshes 55

with a worm 45 provided with a left handed thread and secured to the outer face of the hollow post 16 so that when the post is revolved the worm will rotate the gear 44 in the direction indicated 5 cated by the arrows in Figs. 1 and 3.

The post 16 at its lower end is provided with a flange 46 where the post communicates with the conduit 11. The upper end of the post is mounted in a bearing 47 formed at the upper end 10 of the brackets 42. A grease cup 48 supplies lubricant to the bearing 47. The brackets 42 and bearing 47 may be cast separately from the body and connected thereto in any approved manner.

15 Referring more particularly to Figure 4 it will be seen that a T 50 is threaded at 51 to the upper end of the hollow post 16. The outer ends of hollow legs 52 of the T are internally threaded to receive plugs 53 which are adapted to force 20 the flanged ends 54 on the inner ends of the hollow arms 55 against curved seats 56 formed at the inner portion of the internally threaded members 52. These plugs 53 not only secure the arms 55 in position but they seal the inner ends 25 of the arms against the loss of fluid where these arms join the members 52. The outer ends of these arms 55, as shown in Figure 2, are curved at 57 with a nozzle 58 at each end of the arm for directing the water outwardly therefrom. 30 When the water under pressure is forced from the nozzles 58 these arms will be revolved as will be the post 16 so that the worm gear 45 will revolve the gear 44 for a purpose which will be presently explained.

35 On the rear of the body member 10 is mounted an axle 60 upon which are rigidly mounted the pair of wheels 40 and 41. The outer periphery of each wheel is formed with teeth 61 which engage the ground so that when these wheels are 40 revolved the sprinkler will be propelled forwardly.

The wheel 40, as shown in Figure 1, is provided with an internal set of teeth 62 which are adapted to be engaged by a pawl 63 pivotally mounted at 64 on a lever 65 which has its lower end pivotally mounted on the axle 60. The pawl is provided with a weight 66 for maintaining the pawl in engagement with the teeth 62 at all times. A link 67 has one end pivotally connected at 68 with the upper end of the lever 65 while the 50 other end of the link is pivotally connected to an eccentric pin 69 carried by an arm 70 which is rigid with the shaft 43.

The wheel 41 is also provided with an internal set of teeth as shown at 71 which are adapted 55 to be engaged by a pawl 72 pivotally mounted at 73 upon a lever 74 which is pivotally connected at its lower end to the axle 60. The pawl 72 is provided with a weight 75 which maintains the pawl in engagement with the teeth 71 at all 60 times.

One end of a link 76 is pivotally connected at 77 with the upper end of the lever 74. The other end of the link is pivotally connected to an eccentric pin 78 carried by an arm 79 which is 65 secured to the shaft 43. It will be noted that the arm 70 is located at one side of the gear 44 while the arm 79 is located at the other side. The ends of the arms 70 and 79 are located approximately diametrically opposite.

70 In Figure 5 is shown a modified form of the wheels 40 and 41 in which the internal teeth 62 and 71 respectively of the wheels 40 and 41 are omitted and in this case the teeth 80 of the wheel 40a are so constructed that they will be engaged 75 by a pawl 81 pivotally mounted at 82 at the upper

end of the lever 65a which is pivotally mounted on the axle 60. A spring 83 is employed for maintaining the pawl 81 in engagement with the teeth 80 of the wheel 40a. One end of the link 67a is pivotally connected at 84 to the lever 65a. 5 The other end of the link is adapted to be connected to the eccentric pin 69 on the arm 70.

A link 85 is pivotally connected with the lever 74a similar to the connection between the link 76 and the lever 74 as shown in Figure 3. One end of the link 85 is adapted to be connected to the pin 78 of the arm 79 and a pawl 81a similar to the pawl 81 is adapted to be pivotally connected to the lever 74a so that it will engage the teeth 80a for causing rotation of a toothed wheel 15 41a which is located in parallel relation with the wheel 40a at the opposite sides of the body.

In other words, the only difference between the construction shown in Figure 5 and that shown in Figures 1 to 4, inclusive, is that the pawls 20 engage the teeth 80 and 80a of the power wheels 40a and 41a instead of the pawls engaging teeth formed inwardly and concentrically with respect to the teeth 61 as shown in Figures 1 to 4, inclusive. 25

The operation of the device is as follows: A hose 13 is laid along a definite path on the lawn and the grooved wheel 30 is placed over the hose and the spaced wheels 40 and 41 engage opposite 30 sides of the hose.

When the water is turned on and it issues from the nozzles 58 the arms 55 will be revolved as will be the post 16, the worm 45 and the gear 44. Rotation of the gear directly indicated in Figures 1 and 3 will cause oscillation of the links 35 67 and 76 so that the respective pawls 63 and 72 by their engagement with the respective teeth 62 and 71 will cause rotation of the toothed wheels 40 and 41, whereby the sprinkler will be moved along a path as determined by the position of the hose.

When the sprinkler travels around a curved path the grooved wheel 30 will follow the hose and if the sprinkler tilts too much to one side of the hose one of the curved members 35 on the arm 34 will engage the ground and prevent the sprinkler from falling to one side. At this time the spaced plates 36 will engage the hose and aid in maintaining the body of the sprinkler along the curved path so that the spaced wheels 40 and 50 41 will also be maintained in alignment with the hose.

The construction shown in Figure 5 operates in a similar manner except that the pawls operated by the levers 65a and 74a will engage the 55 teeth at the periphery of their respective wheels, causing the wheels to be revolved and thus propel the sprinkler along a definite path.

The water in this sprinkler enters the hollow post 16 by way of the conduit 11 formed in the 60 body 10 from the hose 13.

I claim:

1. An automotive sprinkler comprising a horizontal body provided with a core forming a conduit, a hollow post having the lower end projecting through the body and terminating in one end of said conduit, a worm secured to the post resting on the upper face of the body for supporting the post on the body, means for supplying the conduit with water under pressure, a combined sprayer and motor connected with the upper end of the hollow post and receiving water under pressure from said post for causing rotation of the post, traction wheels supported at one end of the body, operative connections between the 75

worm and traction wheels, a guide wheel swivelly mounted on the other end of the body, curved arms projecting from opposite ends of the body for engaging the ground to prevent falling of the 5 sprinkler when rounding a curve.

2. An automotive sprinkler comprising a horizontal body provided with a core forming a conduit, a hollow post having the lower end projecting through the body and terminating in one 10 end of said conduit, a worm secured to the post resting on the upper face of the body for supporting the post on the body, means for supplying the conduit with water under pressure, a combined sprayer and motor connected with the upper end 15 of the hollow post and receiving water under pressure from said post for causing rotation of the post, traction wheels supported at one end of the body, operative connections between the worm and traction wheels, and a guiding wheel 20 swivelly mounted on the other end of the body, means cooperating with the grooved wheel for guiding the body along a definite path, and means depending from the body and engageable with the

guiding means for maintaining the traction wheel in line with the path of the grooved wheel.

3. An automotive sprinkler comprising a horizontal body provided with a core forming a conduit, a hollow post having the lower end projecting through the body and terminating in one end of said conduit, a worm secured to the post resting on the upper face of the body for supporting the post on the body, means for supplying the conduit with water under pressure, a combined sprayer and motor connected with the upper end 10 of the hollow post and receiving water under pressure from said post for causing rotation of the post, traction wheels supported at one end 15 of the body, operative connections between the worm and traction wheels, a guiding wheel swivelly mounted on the other end of the body, a bar secured transversely of the body, curved arms depending from the opposite ends of the bars and adapted to engage the ground when the 20 sprinkler tilts to prevent the sprinkler from tilting too far.

JOHN H. WILSON.
